Channing D. Skinner & Dana Read,
Letters Patent.

The schedule referred to in these Letters Patent, and making part of the same, containing a description in the words of the said Channing D. Skinner and Dana Read, themselves of their improvement in the machine for cutting straw and other substances.

To all whom these presents shall come: Be it known that we Channing D. Skinner, of Haddam in the County of Middlesex and State of Connecticut, and Dana Read of Middletown in said County, have invented a new and useful improvement in Machine work for cutting straw, stalks of maize, and similar substances and that the following is a full and exact description of the construction and operation of the said Machine as invented or improved by us. A frame of any suitable wood is made by setting up two end pieces of plank each two feet nine inches high and one inch one half of an inch thick at the distance of two feet and seven inches from each other in the clear. These end pieces are each one foot wide at the bottom, and continue of that width to within about two inches from the top, where they are formed with a gradual increase of width in front, the top of the end pieces on the right being one foot and four inches wide, and the top of the end pieces on the left being one foot and three inches wider. The latter end piece for the sake of firmness is split by mortising into a foot two feet long, three inches wide, and three inches thick. The end pieces are connected together on the back side by five girders one about five inches from the bottom, and the others even with the top, each about five inches wide and one inch and one fourth of an inch thick, and well secured by nuts or screws. The end pieces are connected in front by a similar girder secured in the like manner first below the points where the width

width of the end-pieces begins to increase upon the frame that is constructed is set a wooden feeding box or trough, let down one inch into the end-pieces and laid down with the front, this trough is three feet from inlets long open on the top and at both ends are inlets wide in the center at the right end, and diminishing gradually in width to the left end which is five inches wide. The depth of the trough is six inches at the wider end, and decreases gradually towards the other end which is four inches at the smaller end of this trough a piece of board six inches long and one inch thick is fitted (by means of pivot or wooden pins) as a cover, lying horizontally over with the top, when the trough is full and capable of being readily depressed with the hand as that the earth or other substance diminished, for the purpose of holding it fast. The trough is so made that it projects beyond the left end piece only so as to clear it. At the distance of eight inches in the clear from the left end piece, a scoop with a paper under the trough to which one end is fastened by screws, and the other end is introduced into the lower left girth of the frame, into this left girth and the left end piece, a square iron and shaft three fourths of an inch in diameter, and four inches long with a neck of six inches, is set at the distance of about four inches from the back of the trough in such a manner that the bottom of the trough is on a level with the shaft which remains in iron and is applied with iron. The end of the shaft extends beyond the left girth of the frame three inches and one fourth of an inch, and is fitted with a wheel made of oak wood two feet in diameter and two inches thick. To prevent this wheel from carrying a piece of board four inches wide three fourths of an inch thick is inserted into the outside area a piping through the diameter so as best to counteract any bias in the wood of which the wheel is composed. A pitman of large iron wire is attached to the end of the stand. The lower end of the pitman is secured in any convenient manner to the off side of a wooden tredle two feet long, which extends horizontally from the

The lower back girth of the frame, and is fastened thereto by a hinge joint. The wheel being set in motion by the foot acting upon the handle revolves towards the front. A knife nine inches long and one eighth of an inch thick at the back with its edge turned towards the trough is set on the inner edge of the wheel, parallel with the axis, resting at the ends upon small iron blocks to which it is secured, and which are themselves secured to the wheel in such a manner and position that when the end of theank being raised vertically is just upon the point of descending, the edge of the knife is nearly level with the top of the trough, each of the blocks on which the knife rests is four eighths of an inch thick and the knife in revolving is thus brought into contact with a plate of iron placed at the side of the trough and on the bottom thereof so as to form a sort of shear for cutting the straw or other substance in the trough. The side of the knife next the trough is straight and is bent on the other side. The edge of the knife is somewhat curved inward. The periphery of the wheel is covered with leather draped with a rag for sharpening the knife; and to this end a screw driver accompanies the machine so that the knife may be taken off and put on at pleasure. It is obvious also that the wheel may be used for sharpening other tools. The machine is operated by one person who keeps the wheel in motion with his foot while he supplies the trough with the straw or other substance to be cut, and adjusts it with his hands. The motion ^{may be} produced of desirable by any other power. The machine above described is of the dimensions, which are usually made; but the dimensions and proportions may evidently be increased or diminished to suit the convenience of the operator. The advantages of the machine are that it is portable, simple in its construction, not liable to get out of order, and capable of being repaired with small expense and trouble. We do not claim as an invention or improvement, any one of the parts of the said machine separately considered, but we do claim as an invention and improvement the combination of the various parts

of the said Machine as above described in the said manner, in
thereby to produce the effect of cutting straw, hay, stalks of maize
and like substances with ease and rapidity.
